UNITED STATES PATENT OFFICE.

JOSEPH WASELAK, OF MINNEAPOLIS, MINNESOTA.

VALVE LOCK.

Application filed September 10, 1927. Serial No. 218,826.

My present invention has for its object to provide a simple and highly efficient valve lock intended for general use, but especially adapted for locking the valve in a gas range or stove to prevent the same from being accidentally opened and especially to prevent a child from opening such a valve.

To the above end, generally stated, the invention consists of the novel devices and combinations of devices hereinafter described and defined in the claim.

In the accompanying drawings, which illustrate the invention, like characters indicate like parts throughout the several views.

Referring to the drawings:

Fig. 1 is a perspective view of the improved valve lock;

Fig. 2 is a plan view showing the valve lock applied to a valve of the type commonly used on a gas range or stove;

Fig. 3 is a view partly in elevation and partly in section taken on the irregular line 3—3 of Fig. 2; and

Fig. 4 is a fragmentary view partly in elevation and partly in section taken on the line 4—4 of Fig. 2.

The numeral 5 indicates a plug valve of the type commonly used in gas ranges and stoves and the numeral 6 indicates the casing thereof. This casing 6 is interposed in a gas feed pipe 7 and attached thereto by having on its sides a pair of diametrically opposite nipples 8 screwed into the sections of said pipe.

Secured to the valve 5 is a radial pin 9 which extends into a notch 10 in the upper end of the casing 6 for engagement with a stop shoulder 11 at one end of said notch to limit the closing movement of the valve 5, and a stop shoulder 12 at the other end of said notch to limit the opening movement of the valve 5.

The improved lock includes a box-like body 13 having an open end and a pair of loop-like attaching straps 14, the ends of which are adjustably attached by nut-equipped screws 15 to the bodies thereof. These straps 14 are adapted to be applied around the nipples 8, as best shown in Figs. 2 and 3, for rigidly but detachably connecting the body 13 to the casing 6.

A thumb piece 16 is loosely fitted in the body 13 and attached thereto by a horizontal pivot pin 17 at the open end of the body 13. On the pivoted end of the thumb piece 16 is a lock lug 18, the back of which forms a cam

surface 19. Formed with the upper end of the lock lug 18 is a lateral extension 20. A coil spring 21 is compressed between the bottom of the body 13 and the thumb piece 16. This spring 21 yieldingly holds the thumb piece 16 raised with the lock lug 18 extending into the path of movement of the pin 17 and with the extension 20 positioned to engage the stop shoulder 12 as an abutment. When the valve 5 is closed, its pin 9 projects between the stop shoulder 11 and the lock lug 18, as best shown in Fig. 2, and thereby securely holds the valve 5 closed so that it cannot be turned in either direction. An attempt to open the valve 5 will cause its pin 9 to engage the lock lug 18 which is securely held by the shoulder 12 to resist such pressure.

To release the lock so that the valve 5 may be opened the operator places his forefinger under the body 13 with his thumb on the thumb piece 16 and applies sufficient pressure to move the thumb piece 16 into the body 13 against the tension of the spring 21 and thereby retract the lock lug 18 from the path of movement of the pin 9 to permit the valve 5 to be opened. After the valve is opened and the thumb piece 16 released, the spring 21 will lift the thumb piece 16 and again position the lock lug 18 in the path of movement of the pin 9. When the valve 5 is open, its pin 9 extends under the extension 20, as best shown in Fig. 4.

During the closing movement of the valve 5 its pin 9 engages the cam surface 19 and thereby moves the lock lug 18 against the tension of the spring 21 out of its path of movement. As soon as the pin 9 has passed the cam surface 19 the spring 21 will immediately return the thumb piece 16 and the parts carried thereby to normal position and automatically lock the valve closed.

The above described lock may be very quickly applied to a valve casing and it is evident that it will securely hold a valve from being accidentally opened or from being opened by a child. The body 13 securely protects the thumb piece 16 against accidental movement.

What I claim is:

A lock of the kind described comprising a box-like body having an open top and an open end, said body having at its open end attaching means for securing the same to the casing of a valve provided with a stop pin 105

110

working between a pair of stop shoulders on said casing, said body having a hinged cover affording a lever-acting thumb piece, said cover having a lock lug, and a spring compressed between the cover and body yieldingly holding the cover with the lock lug in the path of movement of the pin to lock the

valve closed, said lock lug having a lateral extension arranged to yieldingly rest on the pin when the valve is open to permit said valve to be set in different open positions.

In testimony whereof I affix my signature.

JOSEPH WASELAK.
